UNITED STATES PATENT OFFICE

2,499,143

BOTTLE COUNTER

John H. Irons, Middlebury, Conn.

Application July 6, 1946, Serial No. 681,739

2 Claims. (Cl. 235—92)

1

This invention relates to bottling machines, and more particularly to an electrically-operated mechanism for counting vertical bottles automatically as they pass through a filling machine, and having means for recording the number of bottles on a counting unit, which may be located at any desired distance from said filling machine.

One object of the present invention is to provide a bottle counting machine of the above nature, in which the bottles passing successively by a fixed point in the filling machine will engage a switch lever for actuating an electromagnetic counter.

A further object is to provide a device of the above nature having a selector unit for adjusting the machine to operate on different sizes of bottles being filled by the machine.

A further object is to provide a device of the above nature which will be simple in construction, inexpensive to manufacture, easy to install and manipulate, compact, ornamental in appearance, waterproof, and very efficient and durable in use.

With these and other objects in view, there has been illustrated on the accompanying drawings one form in which the invention may conveniently be embodied in practice.

In the drawings,

Fig. 1 represents a diagrammatic view of the rotor of a milk bottle filling machine showing the circular path through which the bottles travel as they pass through the machine.

Fig. 2 is a side elevation of the bottle filling machine showing the appearance of the counter-actuating switch lever and associated parts.

Fig. 3 is a plan view of the counter-actuating switch mechanism shown by itself and illustrating in dotted lines two sizes of bottles which may be counted thereby.

Fig. 4 is a side elevation of the same.

Fig. 5 is an end elevation of the same.

Fig. 6 is a plan view of the selector switch of the bottle counting mechanism.

Fig. 7 is a side elevation of the same.

Fig. 8 is a diagrammatic view showing the electrical connections between the contactor switch, the selector switch unit, and the electromagnetic counter units.

By means of the present invention a mechanism has been provided which will automatically count bottles passing through a bottling machine in a dairy or elsewhere, and which will start and stop with said machine and require no attention from the operator. As herein shown, four electromagnetic counters may be selectively em-

ployed to count "quarts," "pints," "one-third quarts," and "one-half pints," respectively, but it will be understood that the same mechanism may be used to count any size or type of bottle containing milk or other liquids.

Referring now to the drawings, in which like reference numerals denote corresponding parts throughout the several views, the numeral 10 indicates a milk bottle which may be of any size within the range of the filling machine which includes a frame F and a rotor 11 upon which bottles are supported during the filling operation.

In order to count the number of bottles passing through the filling machine provision is made of a bottle-actuated contactor lever 12 which is preferably curved and mounted to swing horizontally on a vertical pivot pin 12b carried by an angular bracket plate 12a.

The lever 12 carries a vertical pin 13a connected by a strong coiled spring 19 to a horizontal pin 13b mounted on a switch-supporting plate 13c. Each time the lever 12 is engaged by a bottle 10, it will be swung from the full line position to the dotted line position, shown in Fig. 3, and will release a spring-operated plunger 13, closing a microswitch 14a located within a casing 14 (Fig. 3, 4, 5, and 8).

The successive opening and closing of the switch 14a causes the operation of one of four electromagnetic counters, indicated by the numerals 15, 16, 17, 18, depending upon the size of bottle being filled by the machine.

The filler head of the bottle filling machine is indicated by the numeral 20, and said head includes a plurality of depending nozzles N. The machine also has a vertical central body C.

In order to select the proper electromagnetic counter to correspond with the size of the bottle being filled, provision is made of a link 21 connected to a horizontal pin 22, carried by a pedestal 23 depending from a vertical shaft 23a. The pin 22 is also connected by means of a link 23d to an upper horizontal pin 23e connected in turn to a curved arm 23c, the other end of which is rigidly mounted on a rockable shaft 23b carried by a fixed bracket 23f located on the frame F of the bottling machine.

By means of this construction, by raising and lowering the pedestal 23, the head of the milk bottling machine and the selector mechanism for the counting unit will be simultaneously adjusted to take care of bottling any one of the four different sizes on which the bottling machine may be operated.

The link 21 is connected by means of a lever

25 pivoted on a horizontal pin 26 to an insulated fiber arm 27 carrying a swingable leaf spring contact 24 which is adapted to be connected successively to four stationary contacts 28, 29, 30, 31 mounted on an insulating block 32 on a selector switch casing S. The contacts 28, 29, 30, 31 lead to terminals 32a, 33, 34, 35, which in turn are connected by conductors 36, 37, 38, 39, respectively to the counters 15, 16, 17, 18, as clearly shown in Fig. 8.

The leaf spring contact 24 is connected by a flexible lead 40 to a junction block 41 which is connected by a conductor 42 to the switch 14a. Current is supplied to the electrical apparatus by a pair of line wires 43, 44.

A resistance 45 is included in the supply circuit to reduce the voltage to the electromagnetic counters 15, 16, 17, 18 if found to be necessary. The line wire 44 is connected to the counter units 15, 16, 17, 18 by a common conductor 45a and individual conductors 46, 47, 48, 49. The resistance 45 is joined by a conductor 50 to the other terminal of the microswitch 14a, the conductors 42, 50 being housed in a protective pipe P (see Fig. 2).

Before starting the operation of the bottle filling machine, the filler head 20 must first be raised or lowered and the selector mechanism adjusted accordingly by rocking the shaft 23B and locking the pedestal shaft 23A by mechanism not shown.

Operation

In use, as the bottles 10 successively engage the lever 12, the microswitch 14a will be closed and then automatically returned to open position—thus alternately making and breaking the electrical circuit through the counter apparatus.

One advantage of the present invention is that the plunger 13 of the microswitch 14a will move the same distance at each operation, regardless of the size of the bottle 10, thus reducing wear on said microswitch.

The contacts 28, 29, 30, 31 on the fibrous block 32 are so spaced that when the filler head 20 is locked in position for filling quarts, pints, one-third quarts and one-half pints, selectively, the leaf spring contact 24 will close the particular electric circuit leading to the corresponding magnetic counters 15, 16, 17, 18.

It will thus be understood that there is an individual counter for each size of bottle, and that for whatever size the filler head is set, the correct counter will be in circuit, as shown by the wiring diagram of Fig. 8.

While there has been disclosed in this specification one form in which the invention may be embodied, it is to be understood that this form is

shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a mechanism for counting bottles moving in a predetermined path in a bottle-filling machine of the type which has vertically adjustable means for permitting the filling of bottles of different heights; a switch having an actuating lever extending into said path and adapted to be successively engaged by each bottle for operating said switch, a plurality of electro-magnetically operated counter units, means comprising a selector switch for setting said first-mentioned switch selectively in circuit with any one of said counter units, and linkage means for setting said selector switch in accordance with the elevation of said vertically adjustable means, whereby bottles of different heights may be registered respectively upon different counter units.

2. The invention as defined in claim 1, in which said actuating lever has a spring urging the lever into the path of the bottles so as to be outwardly swung by each bottle, and said first-mentioned switch includes a movable contact, a spring urging said contact to closed position, and an operating element movable through a limited small range and connected with said contact, said lever being swingable through a wide range and normally pressed by its spring against said operating element to hold said contact open, whereby said first-mentioned switch may be actuated by a small initial outward movement of said lever, and differences in the widths of the bottles moving in said path will have no effect upon the operation of said switches or said counter units.

JOHN H. IRONS.
